(57) **CLAIM**

The ornamental design of a disk drive bezel tray, as shown and described.

DESCRIPTION

FIG. 1 is a front, left isometric view of a disk drive bezel tray, showing our new design;

FIG. 2 is a front, right isometric view thereof;

FIG. 3 is a front plan view thereof;

FIG. 4 is a right plan view thereof;

FIG. 5 is a left plan view thereof;

FIG. 6 is a top plan view thereof;

FIG. 7 is a bottom plan view thereof;

FIG. 8 is a front, left isometric view of a second embodiment of the disk drive bezel tray, showing an alternative design of the front; and,

FIG. 9 is a front plan view of the second embodiment.
